(57) **CLAIM**

The ornamental design for an integral power station, as shown and described.

DESCRIPTION

FIG. 1 is a perspective view of an integral power station showing our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines shown on the drawings depict portions of the integral power station that form no part of the claimed design. The dot dash lines in FIGS. 4, 5 and 7 depict the boundaries of the views and do not form part of the claimed design.
